UNITED STATES PATENT OFFICE.

LEWIS L. NETTLETON, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

MICROPHONE.

Application filed August 20, 1925. Serial No. 51,403.

My invention relates to electrical microphones.

I will describe several forms of microphones embodying my invention, and will 5 then point out the novel features thereof in claims.

The present application is a continuation of my co-pending application, Serial No. 744,644, filed October 20, 1924, for microphones, in so far as the subject matter common to the two is concerned.

In the accompanying drawing, Fig. 1 is a view in front elevation showing one form of microphone embodying my invention. 15 Fig. 2 is a vertical sectional view on the line II—II of Fig. 1 looking in the direction indicated by the arrows. Fig. 3 is a front view showing a modified form of microphone also embodying my invention. Fig. 4 is sectional 20 view on the line IV—IV of Fig. 3 looking in the direction indicated by the arrows. Fig. 5 is a detail view showing on an enlarged scale a portion of the microphones illustrated in Figs. 1 and 3. Fig. 6 is a view 25 showing a modified arrangement of the electrical connections shown in Fig. 2. Fig. 7 is a sectional view showing another modified form of microphone embodying my invention.

30 Similar reference characters refer to similar parts in each of the several views.

Referring first to Figs. 1 and 2, the microphone in the form here shown comprises a block A containing two microphone units 35 U¹ and U², which units are located in two circular holes D. The two units are exactly alike and consequently a description of one unit will apply equally well to the other.

Referring to unit U¹, the hole D is provided with a sleeve E of insulating material 40 in which is inserted a bushing G of insulating material. Threaded into bushing G is a stem J, the inner end of which forms a plunger 7 which is located in the sleeve E. 45 The plunger 7 may be adjusted to the desired position by turning the stem J in the bushing G, and may be locked in adjusted position by means of a nut K located on the outside of the bushing G.

50 The front face of the block A is provided with a shoulder 3 having therein a number of grooves 5. Two flat strips 4 and 4^a of elastic material such as spring steel extend across the face of the block A and intersect 55 at substantially right angles at a point which

is in the axis of the sleeve E. The ends of the strips 4 and 4^a are rigidly fastened to the shoulder 3 of block A by means of clamps B which are attached to the block by means of screws 1. Attached to the strips 4 and 4^a by a screw 17 at the point where the strips intersect is a piston N which projects into the sleeve E and is spaced from the plunger 7. This piston is slightly less in diameter than the inside of the sleeve E so that the piston is free to vibrate within the sleeve. 60

A second strip 4^b of spring steel is attached to the block A by clamps B and intersects the strip 4 at a point which is in the axis of the unit U², and the piston N for unit 70 U² is attached to the strips 4 and 4^a by a screw 17^a at the point where these strips intersect.

A mass 10 of finely divided carbon, preferably in the form of globules of uniform 75 size, occupies the sleeve E of each unit between the piston N and the plunger 7. These globules are of course of such size that they do not enter the clearance space within piston N and sleeve E. The resistance of this 80 carbon mass varies in response to changes in the pressure thereon by piston N in the usual and well known manner.

In order to regulate the tension of strip 4 I provide two clamps C the inner sides of 85 which are rounded to conform with the contour of the grooves 5. These clamps are drawn into the grooves by screws 6 so that they force the strip 4 into the grooves and thus increase the tension on the strip as the 90 screws are turned up. This tension adjustment feature is shown more clearly in Fig. 5 than in Fig. 2. The strips 4^a and 4^b are adjusted as to tension in the same manner as strip 4. 95

The pistons N may be vibrated by any suitable means. As here shown vibration of these pistons is caused by an electromagnet L provided with an armature 13 which is carried by a block 14, and this block 14 is 100 in turn connected with the two pistons N by a truss M. When alternating current is applied to the electromagnet L, the two pistons N are caused to vibrate in unison.

The two units U¹ and U² may be included 105 in series or in multiple in the output circuit. As shown in Fig. 2 these units are connected in series in a circuit which includes wires 8 and 9, a battery 18 and the primary of a transformer 19. The secondary of the 110

transformer 19 is connected with one stator winding 20 of an induction motor relay R, the other winding 21 of which may be supplied with alternating current in any suitable manner. The relay R also comprises a rotor 22 and a contact 23. It will be seen that vibrations of the pistons N due to alternating current in the electromagnet L will cause variations of the current from battery 18 in the output circuit and so will cause alternating current to flow in the stator winding 20 of relay R.

As shown in Fig. 6 the two units U^1 and U^2 are connected in multiple in the circuit 15 which includes battery 18 and primary 19.

When the two microphone units are connected in series, the voltage of the battery 18 may be higher than when a single unit is used. When the two units are connected in multiple the microphone as a whole is more stable 20 in operation than when a single unit is employed. With either arrangement of connections I have found that the power output of the microphone is double when two units are 25 employed instead of one.

Referring now to Figs. 3 and 4, the microphone here shown contains but a single unit, and is arranged to use a stack of thin carbon disks instead of the mass of granules shown 30 in Fig. 2. The microphone comprises a block A^1 carrying a supporting member P which is attached to the block by screws 16 and is provided at its upper end with a threaded aperture to receive a threaded post Q extending 35 into the hole D in the block A^1 . The inner end of post Q is provided with an insulated sleeve E^1 which sleeve is surrounded by a stack of thin carbon disks 24. These disks rest against the stop 25 which screws on to the 40 post Q and is locked in adjusted position thereon by a nut 26. The post Q is in turn locked in adjusted position in respect to the support P by means of nuts 10 and 11. In this form the front face of block A^1 is round, 45 so that the shoulder, which is here designated 3^a is annular in shape and the groove 5 is likewise annular. The strips 4 and 4^a are attached to the block A^1 by a single ring B, and are adjusted as to tension by clamps C 50 which co-operate with the groove 5. The vibrating member or piston, which is here designated N^1 , is attached to the strips 4 and 4^a by a screw 17 as in Fig. 1, and is provided with a central recess 27 to receive the inner 55 end of the post Q. This piston bears against the disks 24 so that these disks are held between the piston N^1 and the stop 25. The piston N^1 may be operated by an electromagnet or other suitable device through the medium of a rod M^1 , and the microphone may be connected in an electrical circuit by means of wires 8 and 9.

The following discussion applies to each unit U^1 and U^2 in Figs. 1 and 2 also to the 60 single unit shown in Fig. 3.

One advantage of my invention is that the tension of the strips 4, 4^a and 4^b , and hence the amount of the restoring force, may be accurately, conveniently and permanently adjusted.

Piston N, or piston N^1 , is normally held in an intermediate position wherein the forces acting on the moving parts are in equilibrium; these forces being due to the stiffness of the strips 4, 4^a , and 4^b , and the tension applied to these strips. The piston has, therefore, but one intermediate position of rest. In this respect, a microphone embodying my invention is an improvement over microphones of the type comprising a circular disk 70 diaphragm fixed at its edge, a diaphragm of the latter type being capable of assuming at least two different positions of rest. A further advantage of my invention over microphones having a disk diaphragm is that with 75 the intersecting flat strips a more flexible and more sensitive vibrating system is possible because it is only necessary to apply a comparatively small tension to the strips.

If the strips 4, 4^a and 4^b are placed under 80 a comparatively small tension, the force tending to restore the vibrating system to its position of rest, when the system is moved out of this position, is largely due to the stiffness of the strips and is roughly proportioned 85 to the displacement of the strips. If, however, the strips are subjected to considerable stretch, or tension, the restoring force is due largely to the elasticity of the strips and is 90 then approximately proportioned to the cube 95 of the displacement. By varying the tension of the strips, therefore, I can regulate the variations in the restoring force with displacement for a given strip between wide limits. This feature is an advantage because it is 100 usually desirable for the vibrating system to be biased to its position of rest by a force which varies according to the same law as does the force which drives this system. With my invention I can, by properly choosing 105 the dimensions of the strips, and by properly regulating the tension of the strips, provide any reasonable variations in the restoring force acting upon the vibrating system.

Referring now to Fig. 7, the microphone 115 in the form here shown, comprises a plurality of units arranged for operation in tandem by a single vibrating member. The microphone comprises a shell A^2 , the front or left-hand face of which is similar to the corresponding face of the microphone shown in Figs. 3 and 4; that is to say, two flat strips 4 and 4^a , of spring steel, extend across the face of the shell A^2 and are adjustably attached thereto by an annular clamp B and a plurality of auxiliary clamps C, the inner ends of 120 which are rounded to conform with the contour of the annular groove 5. A threaded rod M^2 is attached to the strips 4 and 4^a where 125 these strips intersect, the attachment being 130

accomplished by a pair of nuts 42 and 42^a. The rod M² may be vibrated by any suitable means, such, for example, as the magnet L and armature 13, shown in Fig. 2.

5 The shell A² contains a plurality of cells, F¹, F² and F³. As here shown, each cell is made up of a hollow cylindrical member 31 of insulating material and a pair of end plates 30 and 32 of electro-conducting material, the 10 end plates 32 and 30 of adjacent cells being separated by a disk 33 of insulating material. The plate 30 at the left-hand end of cell F¹ is electrically insulated from the flange 28 of the shell A² by a disk 29 of insulating material. The elements making up the three microphone units are compressed and held firmly in place by a cap 38 which screws onto the flanged and threaded rear face of the shell A². The right-hand conducting plate 32 of 15 the cell F³ is electrically separated from the cap 38 by a disk 29^a of insulating material. The elements making up the several units are preferably surrounded by a sleeve 41 of insulating material, which in turn is surrounded 20 by a sleeve or tube 40 of metal.

25 The rod M² extends through holes in the plates and disks 29, 30, 32, 33, and 29^a, and is provided with plungers or pistons H¹, H² and H³, which are located in the cells, F¹, F² and F³, respectively. These pistons are spaced by sleeves 43 of insulating material surrounding the rod M².

30 Each cell is packed with granular carbon 49, so that the granules are in electrical contact with the piston H and with the two plates 35 30 and 32 forming the end walls of the cell. It will be seen, therefore, that when the rod M² is moved toward the right, the carbon granules on the right of the piston in each 40 cell are compressed, whereas the pressure on the carbon granules to the left of the piston in each cell is reduced. When the rod M² moves toward the left, the reverse operation occurs. It follows that each cell comprises 45 two microphone relays.

50 Recesses 35 are cut in the sleeves 40, 41 and 31 to accommodate contact fingers 36 and 37, which contact fingers are suitably mounted in the shell A² so that each finger 36 engages with an end plate 30, and each finger 37 engages with an end plate 32.

55 The microphone shown in Fig. 7 may be used with any suitable arrangement of electrical connections. As here shown, it is so connected as to form a part of a "push-pull" amplifier. The three contact fingers 36 are connected by the conductor 47 with one terminal of the primary 45 of a transformer T, whereas the three contact fingers 37 are connected by a conductor 48 with the other terminal of the primary 45. One terminal of a battery 46 is connected with the rod M² and so with each of the pistons H¹, H² and H³, the other terminal of the battery 46 being connected with the middle point of the trans-

former primary 45. The effects of the several microphone units are thus made cumulative to create in the secondary 44 of transformer T an alternating current the frequency of which corresponds with the rate of 70 vibration of the rod M².

75 The amplifier shown in Fig. 7 is particularly advantageous where the input power is comparatively large and where comparatively large power output is desired. Only three cells are shown, but as many cells can be used as desired to meet the requirements of any particular situation.

80 It will, of course, be understood that the clearance between the insulating sleeves 43 and the cell partitions, and also the clearance between the pistons H and the sleeves 31, are sufficient to permit free vibration of the rod and pistons, but not sufficient to permit the passage of the carbon granules.

85 Although I have herein shown and described only a few forms of microphones embodying my invention, it is understood that various changes and modifications may be made therein within the scope of the appended claims without departing from the spirit and scope of my invention.

90 Having thus described my invention, what I claim is:

1. A microphone comprising a flat strip 95 of elastic material, means for rigidly supporting the ends of said strip, other means for varying the tension of said strip, and a vibratable member attached to said strip adjacent the center thereof.

100 2. A microphone comprising a rigid block having a central aperture, a flat strip of elastic material, means for rigidly clamping the ends of said strip to said block leaving the middle portion of the strip free to vibrate, means for varying the tension of said strip, and a vibratable member in said aperture attached to said strip adjacent the center of said aperture.

110 3. A microphone comprising two flat strips of elastic material disposed in substantially the same plane and one strip intersecting the other at an angle near the middle of each strip, means for rigidly supporting the ends of each strip, means for varying the tension of each strip, and a vibratable member attached to said strips adjacent their point of intersection.

115 4. In a microphone, a vibratable member, and means for supporting said member comprising a flat strip of elastic material rigidly supported at its ends, and means for controlling the natural period of said strip by varying the tension thereof.

120 5. A microphone comprising two flat strips 125 of elastic material fastened together adjacent their middle points and intersecting at substantially right angles, means for rigidly supporting the ends of said strips, means for varying the tension of each strip, and a vi-

bratable member attached to said strips adjacent their point of intersection.

6. A microphone comprising two flat strips of elastic material intersecting at a point intermediate the ends of each strip, means for rigidly supporting each end of each strip, means for varying the tension of each strip, and a vibratable member attached to said strips adjacent their point of intersection.

10 7. In combination, a rigid block having a substantially flat surface provided with a groove, a flat strip of elastic material extending across said groove, means for fastening the ends of said strip to said block, means for forcing said strip into said groove to increase the tension of said strip, and a vibratable member attached to said strip intermediate the ends of the strip.

8. In combination, a rigid block having a substantially flat surface provided with a groove, two flat strips of elastic material extending entirely across said groove and crossing substantially at right angles, means for securing the ends of said strips to said block, separate means for forcing each strip into said groove intermediate the ends of the strips, and vibratable means attached to said strips adjacent the point of crossing thereof.

9. A microphone comprising a rigid block having an aperture, a plunger adjustably fixed in said aperture, two flat strips of elastic material crossed substantially at right angles, means for securing the ends of said strips to said block, means for varying the tension of each strip, a vibratable piston in said aperture and attached to said strips adjacent the point of crossing thereof, and carbon granules in said aperture between said piston and said plunger.

10. A microphone comprising an elongated, flat comparatively thin strip of elastic material, means for rigidly supporting the two ends of said strip, other means for controlling the tension of said strip, and a pressure responsive device comprising a vibratable member operatively connected with said strip intermediate the ends of the strip.

11. A microphone comprising a vibratable body means effective when said body is moved out of a position of rest to exert a restoring force upon the body to return the body to said position of rest, and adjusting means for regulating the variation of said force with respect to the displacement of said body.

In testimony whereof I affix my signature.
LEWIS L. NETTLETON.
